UNITED STATES PATENT OFFICE.

EBERHARD SCHNEIDER, OF NEW YORK, N. Y.

CONSECUTIVE-VIEW APPARATUS.

1,153,578.

Specification of Letters Patent. Patented Sept. 14, 1915.

Application filed March 20, 1909. Serial No. 434,618.

To all whom it may concern:

Be it known that I, EBERHARD SCHNEIDER, a citizen of the United States, and a resident of the borough of Manhattan, in the county 5 of New York and State of New York, have invented certain new and useful Improvements in Consecutive-View Apparatus, of which the following is a specification.

This invention relates generally to consecutive view apparatus, and particularly to a cinematographic camera, coacting with indexing and punching appurtenances for the films.

Devices operating in conjunction with the 15 feeding appurtenances, allow the film to come to a full stop when exposed to the field of a lens to produce a sharp cut picture, which is the essential requirement in a device of this kind, so that when the prints 20 produced from the film are represented in rapid succession from a projecting apparatus, the resulting view will be clear and devoid of scintillations.

In the drawings Figure 1 represents a side 25 elevation of the invention with a casing thereof partly broken away, Fig. 2 is an enlarged partial right hand side view of Fig. 1 with the casing removed, Fig. 3 represents a right hand side view of Fig. 2, Fig. 4 is a 30 partial section of Fig. 3 on the line 4-4, Fig. 5 represents a section of Fig. 4 on the line 5-5, Fig. 6 shows a section of Fig. 4 on the line 6-6, Fig. 7 is a partial section of Fig. 5 on the line 7-7, Fig. 8 shows a partial 35 top plan view of Fig. 3, Fig. 9 is a partial enlarged portion of Fig. 1, Fig. 10 shows a portion of an exposed film, and Fig. 11 is a section of Fig. 9 on the line 11-11.

A casing is shown at 15 with the photographic lens 16 and the finder 17. Openings 40 with covers not shown are provided for the casing to enable access to be obtained to the interior thereof. A pair of film boxes 20, 21 parallel to each other are secured within 45 the casing 15 by screws like 22. A sensitive film 23 in the supply box 20 leads over the rollers 24, 25, 26 and after being manipulated by the appurtenances of the invention is led over the swinging rollers 27, 28 to the 50 film take up box 21. A pulley 29 on the axle of the take up box 21 by means of appurtenances to be described causes the film to be wound in the latter box in the usual manner.

A housing for the essential elements of the 55 invention comprises the side walls 30, 31

connected by the front wall 32 and the connecting plates 33, 34. In the front wall 32 are formed three openings 35, 36, 37 and a guide bracket 38 extends from a projection 39 formed with the side wall 30 in the opening 37. Supports 40 and journal bearings 41, 42 extend from the side walls 30 and 31. A support 43 and bearings 44, 45 extend from the side wall 30, and a lug 45 is formed with the side wall 31. An opening 46 is formed in the wall 30, an opening 47 is formed in the wall 31, and a lug 49 extends from the front edge of the wall 30.

A guide plate 50 with the rectangular opening 51 having the slots 52 on opposite sides thereof is secured to the front wall 32 by means of the screws 53, and a guide strip 54 is secured to the plate 50. Guide covers 57 and 58 with conduits 56 are fastened respectively to the front edge of the wall 30 and the guide strip 54. A support 59 is fastened to the cover 57 and a support 60 is fastened to the cover 58. A discharge conduit 61 extends from each of said supports. From the lug 49 extends a hinge pin 62 which latter supports the lugs 63 of the guide door 64 having the handle 65. A spring 66 fastened to the pin 62 has one end 67 thereof bearing on the outer face of said guide door 64, which locates the film 23 in proper position against the guide plate 50 over its opening 51.

On a pin 75 supported in the support 43 of the side 30 are fulcrumed respectively the collars 76, 77 of the curved arms 78 and 79. The collars 76, 77 are maintained in proper lateral position on the pin 75 by means of the stationary collar 80 on said pin. From the collar 76 extends the rear arm 83, and a spring 84 extends between the outer end of the arm 83 and the front edge of the side 30. On the upper end of the arm 78 is formed a boss 86, that supports a pin 87 on which is journaled a roller 89. On the upper end of the arm 79 is formed a boss 92, that supports a pin 93 on which is journaled a roller 95. A spring 96 extends from the arm 79 to the inner face of the side 30. A bracket 100 is fastened to the side 30, has a boss 102 at the upper end thereof from which extends the pin 103 on which is journaled the roller 105.

In the journal bearings 42 formed with the sides 30, 31 is journaled the crank shaft 110 with the crank arm 111 having the han-

dle 112. A spur gear 113 with the grooved pulley 114 is fastened to the crank shaft 110, and a belt 115 connects said pulley 114 with the pulley 29 of the film box 21.

- 5 A bracket 118 with the journal bearing 119 extends from the side 30, and a driven shaft 120 is journaled in said bearing 119, and in the bearings 41 formed with the walls 30 and 31. A flywheel 121 with the hub 123 and a pinion 122 is secured to the shaft 120, the teeth of said pinion meshing with the teeth of the spur gear 113.

An arm 125 has formed therewith the upper forked end 126 and the sleeve 131 15 with the shoulder 132. An oscillating spindle 127 is fulcrumed in the bearing 44 and the sleeve 131 is fulcrumed in the bearing 55, the shoulder 132 bearing on the upper face of the bearing 55. A cam 129 on the 20 shaft 120 oscillates the arm 125 against the tension of a spring 130 extending between said arm and the bracket 118. An arm 124 has formed therewith the upper forked end 138 and the boss 139. The forked end 138 25 is engaged by the cam 140 extending from the hub 123, and the boss 139 is fastened to the spindle 127.

A disk 133 is eccentrically fastened to the shaft 120 and carries the eccentric strap 30 134 from which extends the eccentric arm 135. The latter is fulcrumed on a pin 136 of a reciprocating clamping member 137. The said clamping member has extending therefrom a heel 141 having an opening by 35 means of which it is slidably supported on the guide rod 142 secured in the projection 39 and wall 30. The end of the clamping member 137 opposite the heel 141 bears against a roller 143 journaled on the screw 40 pin 144 in the wall 31. To the heel 141 of the reciprocating clamping member 137 is hinged a clamping wing 145 by means of the pin 146. A spring 147 is fastened to the heel 141 and bears on the edge 148 of the 45 clamping wing 145 to separate the said clamping wing from the main portion of the reciprocating clamp 137. A hinge bracket 153 is fastened to the projection 39 extending from the wall 30, and has hinged 50 thereto the inner clamping wing 155 behind the guide plate 38. A spring 157 is fastened to the hinge bracket 153 and bears against the foot 158 of the inner clamping wing 155.

On the lower end of the sleeve 131 is fastened the boss 156 of the oscillating bracket 160 with the bifurcated upper end 161 in which is journaled the roller 162, that can bear against the clamping wing 145. A boss 164 of an oscillating arm 165 is fastened to 55 the spindle 127 and can bear against the clamping wing 155, against the tension of the spring 166 extending between said arm and the wall 30.

On the shaft 120 is fastened the bevel gear 60 168 the teeth of which mesh with the teeth

of the bevel gear 169 journaled on a journal pin 170 secured in the lug 45 on the wall 31. With the bevel gear 169 is connected the shutter comprising the two members 174 and 175 in the usual way.

70 A pin 176 carrying the arm 177 is pivoted in the supports 40 of the walls 30 and 31. Guides 178 on the arm 177 guide the vertical leg 179 of a bracket having also the horizontal leg 180. The latter leg extends 75 through the opening in the wall 31. A spring 181 has one end fastened to the arm 177 and its other end bears against the vertical leg 179. A cam 185 on the shaft 120 can move the said leg 179, when the latter is located in the path thereof. When the leg 179 is located clear of the cam 185, the arm 177 remains stationary. A spring 186 has one end thereof fastened to the inner 80 face of the front wall 32, and its other end 85 bears against the arm 177.

Two pairs of punches 187 are carried on the arm 177 and register with openings in the guide plate 50. The punches are in the path of the film 23 and are guided in the 90 openings 56 of the guide covers 57 and 58.

An adjusting bracket 193 having the heel 194 and handle 195 is supported on the pin 192 extending from the wall 31. A spring 196 extends from the pin 192 and bears 95 against a screw pin 197 carried on the bracket 193. The heel 194 is represented in the drawings (see Fig. 3) above the leg 180, to maintain the leg 179 in the path of the cam 185. To maintain the leg 179 out of 100 the path of said cam 185, the arm 180 is located above the heel 194.

To operate the apparatus as above described the film 23 leading from the box 20 over the rollers 24, 25, 26, 105, 95, 89 against 105 the guide plate 50, under the guide covers 57, 58, then under the guide door 64 opposite the opening 51, is brought between the reciprocating clamp 137 and the clamping wing 145 thereof. The film 23 then extends 110 between the guide plate 38 and the clamping wing 155. From the latter elements the said film leads into the film box 21 by way of the rollers 27, 28 in the usual way. The film is wound up on the axle of said box, 115 by reason of the rotation of the pulley 29, the said rotation being transmitted to said pulley by means of the belt 115 leading from the pulley 114, the latter rotating with the crank shaft 110. The operator rotates said 120 crank shaft 110 by means of the crank arm 111 with the handle 112. The rotations of said crank shaft are transmitted to the shaft 120 by the interposed gearing. By virtue 125 of the rotations of the shaft 120, the eccentric arm 135 vertically reciprocates the reciprocating clamp 137 with its appurtenances, and the cam 129 on the shaft 120 engaging the forked end 126 of the arm 125, oscillates the sleeve 131. The said oscillating

tions are transmitted to the roller 162 of the oscillating bracket 160, and the said roller 162 intermittently bears against the clamping wing 145 of the reciprocating clamp 137 on its down stroke and carries the film 23 with it. During the up stroke of the reciprocating clamp 137 with its wing 145, at the instant the said up stroke begins, the spindle 127 by virtue of the engagement of 10 the cam 140 with the forked end 138 of the arm 124 causes the oscillating arm 165 to bear against the inner clamping wing 155, to prevent the film moving upwardly or downwardly. It will be noted that the cams 129 15 and 140 operate independently of each other, and that the intervals of time in which the roller 162 and the arm 165 perform their functions can be varied, by varying the relative positions of the cams 129 and 140 with each other, so that the film is 20 clamped and released at the proper times.

The rotations of the shaft 120 are transmitted to the shutter by the gearing interposed between said elements, and when the 25 opening between the members 174 and 175 gages with the opening 51 in the guide plate 50, the photographic lens 16 photographs a view located in the field thereof, said photographing taking place when the film is 30 clamped in position between the guide bracket 38 and the inner clamping wing 155. The light, while the picture is being produced, passes through the slots 52 and photographs index marks or lines 200 on the film 35 23, which may be used for the proper and exact registration of said film when prints are made therefrom or for any other purpose.

When the film 23 is clamped in position 40 and the shutter is covering the opening 51 in the guide plate 50, the punches 187 perforate holes 201, preferably segmental in form, in the edges of said film. The said holes are punched at an appreciable distance 45 from said opening, and at an instant of time, which is either before or after the picture on the film is being produced. The holes may be used for driving the film in the or-

dinary manner in a printing machine or projecting apparatus.

An inspection of the apparatus covering the invention will show that it can, with the usual appurtenances, be used as a picture machine or projecting apparatus, by maintaining the guide door 64 open.

One of the functions of the index marks 200 on the film 23, is to correctly locate said film in a separate punching apparatus. The index marks when used for said punching apparatus are projected on a screen much 50 enlarged, and are made to gage with the permanent marks on said screen, at which instant holes are punched in the film. The punching apparatus will form the subject matter of a separate application.

Having described my invention I desire to secure by Letters Patent and claim:

1. In a consecutive view apparatus the combination of a housing having an opening in the front wall thereof and a slot adjacent 55 to said opening, a lens with its field in line with said opening and slot and means to intermittently move a film over the said opening and slot.

2. In a consecutive view apparatus the 60 combination of a housing having an opening in the front wall thereof and slots at opposite sides of said opening, a lens with its field in line with said opening and slots and means to intermittently move a film 65 over the said opening and slots.

3. In a consecutive view apparatus the combination of a housing, a guide plate for the front of the housing having an opening and slots at opposite sides thereof, a lens 70 with its field in line with said opening and slots, and means to intermittently move a film over the opening and slots in said guide plate.

Signed at the borough of Manhattan, in 75 the county of New York and State of New York, this 17th day of March, A. D. 1909.

EBERHARD SCHNEIDER.

Witnesses:
